DESIGN FOR A SHOE

Bogislavs Zegorav, New York, N. Y., assignor to Valley Shoe Corporation, St. Louis, Mo., a corporation of Missouri

Application July 31, 1935, Serial No. 57,872

Term of patent 3½ years

To all whom it may concern:

Be it known that I, Bogislavs Zegorav, a subject of the King of Sweden, residing at New York city, State of New York, have invented a new, original, and ornamental Design for a Shoe, of which the following is a specification, reference being made to the accompanying drawing, forming a part thereof, in which Figure 1 is a plan view and Figure 2 is a perspective view of a shoe embodying my design.

I claim—

The ornamental design for a shoe, substantially as shown.

BOGISLAVS ZEGORAV.
